LOCK HOOK

Ray G. Boree, Jacksonville, Fla.

Application October 23, 1944, Serial No. 559,974

4 Claims. (Cl. 294—83)

The present invention relates to new and useful improvements in hooks for various purposes, and has for its primary object to provide, in a manner as hereinafter set forth, a device of this character comprising novel locking means.

Another very important object of the invention is to provide a hook of the aforementioned character which may be readily opened while under great strain for releasing the load when desired.

Other objects of the invention are to provide a hook of the character described which will be comparatively simple in construction, strong, durable, highly efficient and reliable in use, compact, and which may be manufactured at low cost.

All of the foregoing, and still further objects and advantages of the invention will become apparent from a study of the following specification, taken in connection with the accompanying drawings, wherein like characters of reference designate corresponding parts throughout the several views, and wherein:

Figure 1 is a view in side elevation.

Figure 2 is a view in front elevation of the device.

Figure 3 is a vertical sectional view, taken substantially on the line 3—3 of Figure 2.

Figure 4 is a side view, showing the hook open.

Figure 5 is a view in vertical section through the open hook.

Figure 6 is a view in transverse section through the upper end portion of the device.

Figure 7 is a view in transverse section through the lower portion of the device.

Referring now to the drawings in detail, it will be seen that the embodiment of the invention which has been illustrated comprises a pair of spaced, opposed, elongated plates 1 and 2 of suitable metal, said plates being longitudinally curved and of substantially the shape shown to advantage in Figures 1 and 5 of the drawings. A tubular rivet or bushing 4 connects one end portion of the plates 1 and 2. The other end portions of the plates 1 and 2 are connected by a solid rivet 5.

Journalized on the rivet 5 and cooperable with the inwardly curved edges of the plates 1 and 2 for retaining the load is a hook 3. Formed integrally with the pivoted end of the hook 3 is a tail member 6.

A metallic latch 7 is journaled on the bushing 4 for swinging movement between the plates 1 and 2. The convex face 8 of the swinging latch 7 is engageable with the concave face 6' of the tail 6 for releasably securing the hook 3 in closed position, as seen in Figure 3 of the drawings.

Formed integrally with the free end of the

swinging latch 7 is a lever 9. Adjacent the concave face 6' on the tail 6 of the hook 3 is an inclined face 10 which is adapted for abutting engagement with the underside of the lever 9 adjacent its junction with the latch 7.

It is thought that the manner in which the device is used will be readily apparent from a consideration of the foregoing.

Briefly, the chain, rope or cable is attached to the device through the bushing 4 and the device is thus suspended in a substantially vertical position, so that the hook 3 will hang in open position by gravity, and the latch 7 hangs loosely between the plates 1 and 2 on the bushing 4. When a load is to be suspended by the hook, the eye or bail attached to the load is moved upwardly against the leg of the U-shaped hook 3 which operates between the side plates 1 and 2, and swings the hook about the rivet 5 so that the tail portion 6 thereof engages the latch 7. Further, upward movement causes the concave face 6' of the tail 6 to ride over the convex face 8 of the latch until downward movement of the latch is arrested by engagement of the lever 9 with the inclined face 10 on the tail 6 of the hook 3. Inasmuch as the concave face 6' is concentric with the axis of the bushing 4 and the convex face 8 follows the contour of the concave face 6' it will be obvious that release of the latch from hook engaging position

30 may be readily achieved by lifting the lever 9.

As best seen in Figure 1 of the drawings, the plate 2 is comparatively narrow and shaped to expose the major portion of the lever 9. Thus, access may be readily had to the lever for manually swinging the latch 7 upwardly so as to disengage the concave face 6' from the convex face 8, thereby permitting the hook 3 to swing to open position. The comparatively wide plate 1 functions as a guard or shield for the lever 9 when the latch 7 is in closed or inoperative position, thereby preventing accidental disengagement of said latch from the hook.

It is believed that the many advantages of a hook constructed in accordance with the present invention will be readily understood, and although a preferred embodiment of the device is as illustrated and described, it is to be understood that changes in the details of construction may be resorted to which will fall within the scope of the invention as claimed.

What is claimed is:

1. A self-latching hook which includes a frame comprising a pair of spaced parallel side plates of arcuate configuration, a bill extending forwardly from the upper end of each side plate, a

suspension bushing extending transversely between the side plates adjacent their bills, a hook supporting rivet extending transversely between the side plates near their lower ends, a U-shaped hook pivotally supported from its bight portion on the rivet between the side plates, the end of one leg of the hook cooperating with the bills when the hook is closed to form a wholly closed loop, the other leg of the hook lying flush with the concave edges of the side plates when the hook is closed whereby the hook may be moved to closed position by contact with a load supporting element, and a latch pivotally supported on the bushing releasably to hold the hook in closed position.

2. A self-latching hook which includes a frame comprising a pair of spaced parallel side plates of arcuate configuration, a bill extending forwardly from the upper end of each side plate, a suspension bushing extending transversely between the side plates adjacent their bills, a hook supporting rivet extending transversely between the side plates near their lower ends, a U-shaped hook pivotally supported from its bight portion on the rivet between the side plates, the end of one leg of the hook cooperating with the bills when the hook is closed to form a wholly closed loop, the other leg of the hook lying flush with the concave edges of the side plates when the hook is closed whereby the hook may be moved to closed position by contact with a load supporting element, a latch pivotally supported on the bushing between the side plates and a shoulder on the latch for engaging the end of the leg of the hook opposite that which cooperates with the bills releasably to hold the hook in closed position.

3. A self-latching hook which includes a frame comprising a pair of spaced parallel side plates of arcuate configuration, a bill extending forwardly from the upper end of each side plate,

a suspension bushing extending transversely between the side plates adjacent their bills, a hook supporting rivet extending transversely between the side plates near their lower ends, a U-shaped hook pivotally supported from its bight portion on the rivet between the side plates, the end of one leg of the hook cooperating with the bills when the hook is closed to form a wholly closed loop, the other leg of the hook lying flush with the concave edges of the side plates when the hook is closed whereby the hook may be moved to closed position by contact with a load supporting element, a latch pivotally supported on the bushing releasably to hold the hook in closed position, and a lug on the latch projecting in a direction opposite the direction of closing movement of the hook for releasing the latch.

4. A self-latching hook which includes a frame comprising a pair of spaced parallel side plates of arcuate configuration, a bill extending forwardly from the upper end of each side plate, a suspension bushing extending transversely between the side plates adjacent their bills, a hook supporting rivet extending transversely between the side plates near their lower ends, a U-shaped hook pivotally supported from its bight portion on the rivet between the side plates, the end of one leg of the hook cooperating with the bills when the hook is closed to form a wholly closed loop, the other leg of the hook lying flush with the concave edges of the side plates when the hook is closed whereby the hook may be moved to closed position by contact with a load supporting element, a latch pivotally supported on the bushing releasably to hold the hook in closed position, a lug on the latch projecting in a direction opposite the direction of closing movement of the hook for releasing the latch, and a guard on one of the side plates to protect the lug from accidental movement.

RAY G. BOREE.
